No. 734,886.

PATENTED JULY 28, 1903.

T. J. KIERNAN.

STEAM VALVE.

APPLICATION FILED MAY 8, 1903

NO MODEL.

THE NORRIS PETERS CO., PHOTO-LITHO., WASHINGTON, D. C.

UNITED STATES PATENT OFFICE.

THOMAS J. KIERNAN, OF COLUMBIA, SOUTH CAROLINA, ASSIGNOR TO THE BROOKS IMPROVED STEAM VALVE COMPANY, OF COLUMBIA, SOUTH CAROLINA, A CORPORATION OF SOUTH CAROLINA.

STEAM-VALVE.

SPECIFICATION forming part of Letters Patent No. 734,886, dated July 28, 1903.

Application filed May 8, 1903. Serial No. 156,254. (No model.)

To all whom it may concern:

Be it known that I, THOMAS J. KIERNAN, a citizen of the United States, residing at Columbia, in the county of Richland and State of 5 South Carolina, have invented certain new and useful Improvements in Steam-Valves; and I do hereby declare the following to be a full, clear, and exact description of the invention, such as will enable others skilled in 10 the art to which it appertains to make and use the same.

This invention relates to improvements in valve mechanism of the Corliss or rocking type; and it consists in providing a valve 15 with multiple passages for the admission of live steam and the escape of the exhaust-steam, so that a slight rocking motion of the valve will quickly open and close the steam and exhaust ports.

20 The valve is provided with vertical passages in its sides and with axial passages at its top and bottom, so as to secure a quick feed and a quick exhaust, more especially a quick and ample exhaust.

25 The valve is so arranged that steam is supplied both from near the top and near the bottom of the steam-chest at the same time.

The valve is intended more especially for use for locomotive and like high-speed recip- 30 roating engines or for engines having a short stroke, where it is difficult to secure a quick enough exhaust.

35 Live steam under higher pressure flows faster than exhaust-steam at a reduced pressure, and therefore it is ordinarily more difficult to secure a quick exhaust than it is to secure a quick supply of steam, and the herein-described valve is specially adapted to insure a quick exhaust.

40 The invention will be understood by reference to the accompanying drawings, in which—

45 Figure 1 shows a longitudinal section through the upper part of the cylinder and the steam-chest, the section being along the line 11 of Fig. 2; and Fig. 2 shows a section along the line 22 of Fig. 1 looking in the direction of the arrows.

A represents the cylinder, a part only of which is shown. Secured to the cylinder in 50 any convenient way or cast integral therewith, if preferred, is the steam-chest B, on which the cap B' is secured by the tie-bolts B².

C and C' (shown in dotted lines) indicate the steam-passages opening into the steam- 55 chest from the boiler.

D represents a curved valve-seat provided with passages d and d', connected to the ports a and a', leading to the opposite ends of the cylinder. The valve-seat is also provided 60 with the exhaust-passage d², opening into the exhaust-passage a², connected either to the atmosphere in the usual way or to the condenser, if one be used.

E represents the valve, which is rocked on 65 its seat by the valve-stem, operated by any suitable mechanism for imparting reciprocal motion. The valve E is provided with cylindrical ends E', which bear below on the valve-seat and above on the balance-plate H. 70 The central portion E² of the valve is hollowed out rectangularly, as indicated in Fig. 1, and into this rectangular portion passes the rectangular part F of the valve-stem. The slot in the valve is slightly longer than 75 the vertical thickness of the valve-stem, so as to allow the valve a slight vertical play therein, (indicated by the spaces e⁶ and e⁷.) Thus the space e⁶ allows the valve to open should the cylinder be filled with water and 80 excessive strain be brought on the valve, while the space e⁷ allows the valve to settle down and compensate for wear on the valve-seat.

For convenience in assembling the part F 85 of the valve-stem is made eccentric to the pivots F' and F² thereof and the part F is slid into the stem through an opening which is afterward closed by the plate B³, carrying the yoke B⁴ and the gland b⁵. The valve is 90 provided with webs extending axially, (indicated by the letters e, e', e², e³, e⁴, and e⁵,) which leaves passages 1, 2, 3, 4, 4^a, 3^a, 2^a, and 1^a in the sides of the valve, as shown in Fig. 1, with axial passages 5 and 6 at the bottom and 95 top of the valve, respectively. These pas-

sages in the side of the valve are substantially parallel to each other and to the axis of the valve.

- Above the valve is mounted the balance-plate H, having a passage h with a small opening h^0 into the balance-chamber on top of said balance-plate. This balance-plate is mounted to move vertically between the guides K² of the guide-block K, which guide-block is provided with transverse passages K', so that steam may pass freely from one side of the steam-chest to the other. Between these transverse passages are ribs k, in which are screwed the supporting-bolts L.
- M represents packing-strips placed between the top of the balance-plate and the lower face of the guide-block, which strips are normally pressed upward by means of springs M', mounted in pockets h' in the balance-plate H. The balance-chamber above the plate H being connected by the opening h^0 to the exhaust, there will be very little pressure on the top of the said plate inside of the packing-strips M, while steam will pass up in the clearance-space between the guide-block and the balance-plate and will press down on the top of the balance-plate exterior to the strips M, thus diminishing the downward pressure that the balance-plate would normally have upon the valve.

P represents the ordinary lubricating-pipe connected to any suitable lubricator. (Not shown.)

- The operation of the device is as follows:
- Suppose the valve to be in the vertical position—that is, with the rectangular portion F vertical. At this time all of the ports would be closed. A slight rocking motion of the valve, say, to the left would partially open the exhaust-port d' and would also begin to open the top of the passage 3^a through the passage h, so that the exhaust-steam would begin to flow through the passage 5 into the exhaust and also through the passages 3^a, 6, 4^a and 4^a to the passage 5 and thence to the exhaust. A slight further movement of the valve will further open the exhaust-passages and will begin to open the passage 1 to the passage d and the top of the passage 2 to the steam-chest, thus permitting live steam to pass through the passages 1 and 2 to the port a. When the valve is rocked to the position shown in Fig. 1, the steam-passages will be opened wide, and also the exhaust-passages will be opened wide. Thus by this arrangement a short travel of the valve will open two steam-ports, one at the top and one at the bottom of the valve, securing a quick feed of steam, while a very quick opening of the exhaust-passages is secured.

Having thus described my invention, what I claim, and desire to secure by Letters Patent of the United States, is—

1. In a steam-engine, the combination with a cylinder provided with steam and exhaust

ports and a curved valve-seat, of a substantially cylindrical valve mounted transverse to the cylinder and rocking on said valve-seat, the said valve being provided with a plurality of passages in each side, and axial 70 passages in the top and bottom, a curved balance-plate on the top of said valve, a guide-block engaging said balance-plate, and an exhaust-chamber above said balance-plate and tending to decrease the downward pressure of the same on the valve, substantially as described.

2. In a steam-engine, the combination with a cylinder provided with steam and exhaust ports and a curved valve-seat, of a substantially cylindrical valve mounted transverse to the cylinder and rocking on said valve-seat, the said valve being provided with passages in each side of said valve substantially parallel to the axis thereof and extending 80 through the valve-body, axial passages at the top and bottom of said valve, a curved balance-plate bearing on the top of said valve, a guide-block mounted in the steam-chest and holding said balance-plate in place, and 85 packing-strips interposed between said balance-plate and said guide-block to form a balance-chamber connected to the exhaust, substantially as described.

3. In a steam-engine, the combination with 95 a cylinder provided with steam and exhaust ports and a curved valve-seat, of a substantially cylindrical valve rocking on said valve-seat, provided with a plurality of substantially parallel passages in the sides of said 100 valves and extending therethrough, and axial passages in the top and bottom of said valve connected to innermost side passages, substantially as described.

4. In a steam-engine, the combination with 105 a cylinder provided with steam and exhaust ports and a curved valve-seat, of a substantially cylindrical valve mounted transverse to the cylinder and rocking on said valve-seat, the said valve being provided with a 110 plurality of passages in each side, and axial passages in the top and bottom, connected to the exhaust, a curved balance-plate on the top of said valve, a guide-block engaging said balance-plate, and a chamber above said 115 balance-plate connected to the exhaust and tending to decrease the downward pressure of the same on the valve, substantially as described.

5. In a steam-engine, the combination with 120 a cylinder provided with steam and exhaust ports and a curved valve-seat, of a substantially cylindrical valve mounted transverse to the cylinder and rocking on said valve-seat, the said valve being provided with 125 passages in its sides substantially parallel to the axis thereof and extending through the valve-body, also with axial passages at the top and bottom of said valve, connected to the inner side passages, a curved balance-plate bear- 130

ing on the top of said valve, a guide-block mounted in the steam-chest and holding said balance-plate in place, and packing strips interposed between said balance-plate and said guide-block to form a balance-chamber connected to the exhaust, substantially as described.

In testimony whereof I affix my signature in presence of two witnesses.

THOMAS J. KIERNAN.
